UNITED STATES PATENT OFFICE.

ISAAC W. WEPPLO, OF CHICAGO, ILLINOIS.

LOCKING JAWS.

1,411,824.

Specification of Letters Patent. Patented Apr. 4, 1922.

Application filed November 15, 1920. Serial No. 424,255.

To all whom it may concern:

Be it known that I, ISAAC W. WEPPLO, a citizen of the United States, and resident of Chicago, in the county of Cook and State 5 of Illinois, have invented new and useful Improvements in Locking Jaws, of which the following is a specification.

This invention relates to a device attachable to relatively movable objects for the 10 purpose of locking such objects against relative displacement.

The object of my invention is to provide a simple and inexpensive device of the character referred to, which may be attached to 15 sliding doors or other similar mechanisms, without making special preparations for such attachment. To this end my invention consists in the combinations hereinafter described, and a drawing is hereto annexed, in 20 which a structure embodying the invention is illustrated as applied in practice.

In the drawing:

Fig. 1 shows my invention locked in place on a sliding elevator door,

Fig. 2 illustrates the device as it appears 25 when opened and removable, and

Fig. 3 shows a slightly modified form of my invention.

The elevator door comprises an upwardly 30 slidable portion 1, and a downwardly movable member 2. Such doors are usually made of corrugated sheet metal, as indicated in the drawing by the reference numerals 3 and 4, and the abutting edges are reinforced 35 by securing an angle bar 5 to the bottom edge of slide 1, and a corresponding bar 6 to the top edge of the member 2. In the folds of the corrugations of said slides and within the flanges of the angle bars are thus 40 provided pockets into which the structure of my invention may be inserted, as clearly illustrated.

This structure of my invention takes the 45 shape of a pair of jaws 7 and 8, and these jaws may be identically shaped as indicated, in order to reduce the manufacturing cost of same. The jaws are pivotally combined by means of a rivet 9, and they are locked together in closed position by means of a suitable padlock 10. The shape of each jaw is important, as will be observed upon examination of the drawing, partly on account of its compactness and strength and also because the structure presents no projecting

corners capable of causing injury to a person passing or stationed near the door to which the structure is attached. 55

Each jaw is substantially shaped like a capital L, and it is provided with a perforation 7^a at the top and one 7^b at the apex, (it 60 being noted that the L 7 in the drawing is shown inverted). The hooks 7^c, 8^c are shaped to project over the edges of the angle bars, and the only requirement is that they must be at least as strong as the door 65 structure, in order that the latter may break first, in case an intruder attempts to break the jaws away from the door. And as the jaws may be made from hardened steel, such strength may easily be attained. 70

Now it may be said that not all doors, or similar sliding structures, are made from corrugated sheet metal. For the purpose of fire protection and in order not to make them unduly heavy they are mostly so constructed. 75 But even wooden doors, as indicated in Fig. 3, may be locked by means of my invention. For this purpose I provide jaws 12, 13, with sharpened hooks 12^a, 13. A few taps with a hammer causes said hook to penetrate into 80 the wood, and to lodge behind the reinforcing bars 14, 15, with which such wooden doors always are provided. And once the jaws have been driven into place, they may thereafter be inserted in the pockets thus 85 created.

I claim:

1. The combination with the abutting edges of a sliding door, of a pair of pivotally combined jaws capable of engaging said edges, and means for locking said jaws against disengagement. 90

2. The combination with the abutting edges of a sliding door having reinforcing bars along said edges, of a pair of pivotally 95 combined hooks insertable behind said bars, and means for locking said hooks together.

3. The combination with the abutting edges, of a sliding door having reinforcing bars along said edges, of a pair of pivotally 100 combined jaws having hooks capable of insertion behind said bars when the jaws are closed, and provided with perforations brought into registration when the jaws are thus closed, and means engaging said 105 aligned perforations for locking the jaws in closed position.

4. A locking structure comprising two

identical L shaped levers, each of which has a perforation at the top and one at the apex, said levers relatively inverted in order to bring the top perforation of one into line 5 with the apex perforation of the other, and a member engaging said aligned perforations for pivotally combining the structure.

5. As an article of manufacture a pair of L shaped levers perforated at the top and at 10 the apex and relatively inverted, a pivot engaging the top perforation of one with the apex perforation of the other, said remaining two perforations capable of alignment

when the levers are swung into closed position for the accommodation of locking 15 means.

6. The combination with the abutting edges of a wooden sliding door having reinforcing bars along said edges, of a pair of pivotally combined jaws insertable behind 20 said bars for the purpose of maintaining the door closed, said jaws provided with sharpened points capable of penetrating into the wood behind said bars, and means for locking the jaws together.

ISAAC W. WEPPLO.
